UNITED STATES PATENT OFFICE.

HENRY E. KIRSTEIN, OF ROCHESTER, NEW YORK, ASSIGNOR TO E. KIRSTEIN SONS COMPANY, OF ROCHESTER, NEW YORK, A CORPORATION OF NEW YORK.

DESIGN FOR SPECTACLE-TEMPLE END.

6,365.

Specification for Design.

Patented Oct. 5, 1920.

Application filed March 24, 1919. Serial No. 284,779. Term of patent 14 years.

To all whom it may concern:

Be it known that I, HENRY E. KIRSTEIN, a citizen of the United States, residing at Rochester, in the county of Monroe and State of New York, have invented a new, original, and ornamental Design for a Spectacle-Temple End, of which the following is a specification, reference being had to the accompanying drawing, forming a part thereof.

Figure 1 of the drawings is a plan view of the temple end; and

Fig. 2 is a view of one side of the temple end, both showing my new design.

I claim:

The ornamental design for a spectacle temple end, as shown.

HENRY E. KIRSTEIN.
